[57] **CLAIM**

The ornamental design for a control pushbutton for a radio receiver or the like, as shown and described.

DESCRIPTION

FIG. 1 is a front, top and left side perspective view of a control pushbutton for a radio receiver or the like showing my new design;

FIG. 2 is a front elevational view thereof;

FIG. 3 is a left side elevational view thereof;

FIG. 4 is a bottom plan view thereof;

FIG. 5 is a right side elevational view thereof; and FIG. 6 is a fragmentary cross-sectional view thereof taken along line VI—VI in FIG. 2.

The broken line showing is for illustrative purposes only and forms no part of the claimed design.
